UNITED STATES PATENT OFFICE.

FRANK MICHEL SMITH, OF BEND, OREGON.

CIRCUIT CONTROLLER.

Application filed September 9, 1920. Serial No. 409,150.

To all whom it may concern:

Be it known that I, FRANK MICHEL SMITH, a citizen of the United States, and a resident of Bend, in the county of Deschutes and State of Oregon, have invented certain new and useful Improvements in Circuit Controllers, of which the following is a specification.

This invention relates to circuit controllers especially adapted for use in connection with signalling systems on automobiles and the like.

Briefly stated, an important object is to provide a circuit closer or controller where-in the manual rotation of a crank results in successively opening and closing a circuit for energizing a horn or the like at short intervals.

In the accompanying drawing forming a part of this application and in which like numerals are employed to designate like parts throughout the same,

Figure 1 is a view in front elevation of the improved circuit controller.

Figure 2 is a vertical transverse sectional view taken on the line 2—2 of Figure 1.

Figure 3 is a detail view showing in front elevation a contact ring forming a part of the circuit controller.

Figure 4 is a rear elevation of the contact ring.

Figure 5 is a detail sectional view taken on line 5—5 of Figure 4.

Figure 6 is a detail sectional view taken on line 6—6 of Figure 4.

Figure 7 is a perspective of a contact element embodied in the invention.

In the drawing, the numeral 32 designates a shaft adapted for operating one or more visual indicators which form no part of this invention and as illustrated in Figure 2 the upper portion of the shaft 32 is provided with a pinion 34 which meshes with a second pinion 35, both of said pinions being enclosed within a housing 33. It might be stated that the housing 33 is secured in any suitable manner to the rear side of a casing K within which a circuit controlling mechanism is located.

As shown in Figures 1 and 2, the forward side of a casing K is formed at intervals of 90° with notches 39, any one of which is adapted to receive the lug 39^a formed on the inner side of the crank 37, for effecting the temporary locking of the crank in any one of its four positions. The casing is also

provided with a stop L which is designed to prevent complete rotation of the crank 37.

As illustrated to advantage in Figure 2, the casing K houses a circuit controller, such controller comprising, in the present instance, a ring R, a contact plate P, and a contact arm C. The ring R is formed of insulating material, and is provided with flat sides, the rear side of which is formed with recesses as shown in Figure 4. As shown in Figures 4, 5 and 6, the periphery of the ring is embraced by the contact plate P, such plate being formed of conducting material and secured to the ring by retaining lugs 40, and provided with offset contact segments 41 which respond within the recesses of the ring. As shown in Figures 3 and 4, the inner edge of the ring is slotted diagonally preferably at intervals of 90° as indicated at 42 at points corresponding to the notches 39 of the casing K.

The contact arm C is preferably constructed in the manner shown in Figure 7, the same being provided with a hub 43, a shank 44 having convex sides, and a flexible portion 45 connecting the hub with the shank. As shown in Figure 2, the contact arm in its applied position within the casing K has its hub 43 fixed to the shaft 36 with the shank 44 engaging the ring R. The contour of the shank and the positioning of the contact arm with respect to the ring is such that the flexible portion 45 normally urges the shank to a position medially of the opposite sides of the ring R. By virtue of this arrangement, and the formation of diagonal slots 42, it will be clear that the contact arm C in the vertical position shown in Figure 2, reposes within the uppermost diagonal slot 42. When moving the contact arm to the left from this position, the walls of the diagonal slot will engage the convex surfaces of the shank 44, thereby guiding the contact arm to the rear side of the ring R. Upon continued movement of the arm to the left, the shank engages the two segmental contacts 41 to the right of the uppermost slot as when viewed in Figure 4. When the contact arm reaches the intermediate slot 42 to the left, the flexible portion 45 serves to move the shank to the medial position so that when the contact arm is returned to vertical position, the shank will engage the walls of the diagonal slot and thus move the contact arm to the forward side of the ring, so that during the return

movement of the contact arm it does not engage the two aforementioned contacts.

The operation of the contact arm when moving to the intermediate slot at the right 5 from the lowermost slot, is the same as that just described, so that during the downward movement of the contact arm it will engage the contact segments on one side of the ring, and when returning the same to its 10 normal position, it will move over the forward side of the ring to disengage such contacts. This particular mode of operation is designed for the purpose of causing the 15 horn having electrical connection with the contact segment 41 to sound a predetermined number of times when moving the signals to any of the indicating positions.

As will be understood, the contact arm C constitutes one terminus of the circuit of 20 the horn while the plate P and its several contact segments constitute the other terminus. It will therefore be seen that when the crank 37 is moved to any one of its four positions, the contact arm C is caused to engage the contact segments 41 disposed in its 25 path and to thereby effect an energization of the horn each time the contact arm engages a segment.

Although I have herein shown and described only one form of my invention, it is to be understood that various changes and modifications may be made without departing from the spirit of the invention or the spirit and scope of the appended claims.

35 I claim:—

1. A circuit controller comprising a ring, formed of insulating material, said ring being formed with recesses on one side there-

of and diagonally arranged slots on its inner periphery, a conducting plate secured to 40 the ring and including segmental contacts disposed within said recesses, and a contact arm urged to a medial position with respect to the sides of said contact ring.

2. A circuit controller comprising, a ring 45 formed of insulating material, the inner periphery of said ring being formed of diagonally extending slots arranged in pairs, the slots of each pair reversely disposed with respect to the slots of the other pair, a conducting plate embracing the periphery of 50 said ring and including contacts disposed at one side of said ring, and a contact arm mounted axially of the ring and urged to the medial position with respect to the opposite sides of the ring, and means for rotating said contact arm whereby, the walls of said slots function to guide said arm to engage one side of the ring when moved in one direction and to engage the 55 other side when moved in the other direction.

3. A circuit controller comprising, a ring 60 formed of insulating material, the inner periphery of said ring being formed of diagonally extending slots arranged in pairs, the slots of each pair reversely disposed with respect to the slots of the other pair, a conducting plate embracing the periphery of 65 said ring and including contacts disposed at one side of said ring, and a contact arm mounted axially of the ring and comprising, a hub, a shank having convex sides, and a flexible portion connecting said hub and shank.

FRANK MICHEL SMITH.
